UNITED STATES PATENT OFFICE

2,309,153

HEEL-ATTACHING MACHINE

William W. Wooldridge, Beverly, Mass., assignor
to United Shoe Machinery Corporation, Flem-
ington, N. J., a corporation of New Jersey

Application October 2, 1941, Serial No. 413,245

10 Claims. (Cl. 1—32)

My invention relates to machines for attaching heels to shoes, it being especially concerned with the pressure mechanism or holdown by which a heel is clamped upon the heel-seat of a shoe for the fastening-inserting operation.

In the nailing of heels to shoes, a well known holdown mechanism is of the compensating type, in which an interconnection between members which engage, respectively, the tread and rear of a heel, communicates the movement of one member to the other. After the engagement of both members has been established, this interconnection equalizes the pressure applied and for most forms of heels furnishes very effective displacement-preventing means. When, however, the rear of a heel is relatively straight, as in the Cuban type of heel, there is a tendency for the rear member, which is in the form of a fork, to slide down the heel. This allows the tread member to rise, so the heel is forced forward out of position upon the heel-seat of the shoe. To overcome this difficulty, a common practice is to secure the two heel-engaging members against relative movement, utilizing the tread member only to effect the clamping of the heel. Under these conditions, in applying the heel to the heel-seat, the operator must both locate it transversely and hold the breast properly up to the cut or shoulder upon the outsole. This is difficult to accomplish satisfactorily, and an object of my invention is to ensure a tight joint at the heel-breast without effort on the part of the operator. In the attainment of this object, in a pressure-head movable toward and from a support for a shoe and heel, I combine with a tread-engaging member or plate a member, preferably in the form of a spring-actuated plunger, yieldable upon the head and contacting with the rear of the heel before the engagement of the associated member with the tread. This rear member thrusts the breast of the heel against a co-operating surface of the sole, and, as it yields, holds the heel firmly in place while the descent of the tread member applies clamping pressure. To permit the correct engagement of the holdown with heels differing in form, the pressure-head may carry a plurality of the rear members, as the yieldable plunger and the customary fork, together with means arranged to secure one of them in either an active or an inactive position. The fork may be free to slide transversely upon its mounting, so it will adapt itself to the heel as located by the operator. The invention is herein disclosed in connection with a compensating heel-holdown, in which two racks guided in

5 a pressure-head are caused to move together by an intermediate pinion, which racks may be secured against relative movement for use in connection with straight-back heels. When the racks are thus held, my yieldable member contacts with the heel to urge it into position to receive the clamping effect of the tread member. When the rear fork is to be used instead of the yieldable member or plunger for the retention of 10 heels more inclined at the rear, said plunger may be secured in its mounting in an inactive position.

The accompanying drawing illustrates one of several possible embodiments of the invention,

15 Fig. 1 showing my improved holdown in broken side elevation and out of clamping relation;

Fig. 2 being a similar view with the heel clamped for the operation upon it;

Fig. 3, an elevation, looking from the right in 20 Fig. 1, of the engaging members for the rear of the heel; and

Fig. 4, a top plan view of said members.

At 13 appears the jack of a machine designed 25 for the attachment of heels to shoes by nails driven from within. A shoe S is shown as supported upon the jack with a heel H upon its heel-seat. Nails N are inserted by drivers 12 reciprocating in passages in the jack. Co-operating 30 with the jack is a head P, generally of a form well known, and movable vertically upon the frame of the machine to first apply to the work preliminary pressure, while the heel is being located upon the heel-seat by the operator, and then final pressure to clamp the work during the 35 driving of the nails. Upon the head, a slide 14 is adjustable horizontally from front to rear of the machine by a screw 16. Guided for vertical reciprocation in the slide are two parallel rack-bars 18 and 20. The front bar 18 carries at its lower extremity a plate 22, adjustable as to angle by a screw 24 and adapted for engagement with the tread-surface of the heel. Pivoted 40 for angular adjustment upon the rear bar 20, retained by a detent device 26, is a mounting 28 by which is carried a fork 30 for engagement with the rear of the heel and the heel-engaging device or pushing finger E of this invention. Meshing with the opposed teeth of the two rack-bars is a pinion 32, rotatable in the 45 slide and communicating the movement of either bar oppositely to the other. An expansion-spring 34, interposed between the bar 18 and the slide 14, biases the pressure mechanism to hold the tread-plate 22 normally down and the mounting 50 28 raised. The compensating effect of the gear- 55

ing upon the tread and rear heel-engaging members may be eliminated by inserting a pin 36 in registering openings in the slide and front rack-bar, this locking the tread-plate at or near its lowest position and the rear member elevated.

Considering now the features peculiar to my invention, the mounting 23 has attached at its lower reduced rear portion 33 by screws 40, 40 a bracket 42. Pivoted upon the bracket at 43 is the divided head 44 of a spindle 43. Slidable upon the spindle is a casing 48, retained against displacement by a pin 56 set in the spindle and projecting into slots 52 in the casing. The casing is urged normally outward upon the spindle, in a direction generally longitudinal of the bottom of a jacked shoe, by an interposed expansion-spring 54, thus furnishing a spring-actuated plunger. The finger E may be located in an active position, ready for engagement with the rear of a heel upon the jack 10, as appears in full lines in Fig. 1, or in an inactive position clear of the work, as indicated in dotted lines. In either position, it may be secured by a pin 56 attached to the bracket 42 and inserted in aligned openings in the finger-head 44, and in the respective openings 60 or 62 in the bracket and with which the head-openings are selectively brought into registration. To retain it conveniently for use, the pin may be attached to the bracket by a chain 64. The lower extremity of the casing is cushioned by a covering 66 of some such material as leather, retained in place by screws 67.

The fork 30 is preferably arranged to slide at the front of the mounting portion 33. It has a tongue or projection 68 movable along a transverse groove in the portion 33, the tongue being retained in the groove by a screw 72 passing through a transverse slot 74 in said portion 33 and being threaded into the body of the fork, where it is secured by a check-nut 76. The head of the screw 72 is recessed into the bracket 42 at 78. The inner or heel-engaging surfaces of the fork are, like the finger E, cushioned at 80 with leather, or the like, held by clamp-bars 82 and screws 84.

Assuming that the holdown of this invention is to be employed in connection with the attachment of a heel H having relatively little pitch, such as that illustrated in Figs. 1 and 2, the operator, inserting the pin 36 in the openings in the slide 14 and in the front rack-bar 13, secures the tread-plate 22 in its lowered relation. The fork 30 is correspondingly raised, while the cushioned end of the finger E projects below the fork, it being there held by the pin 56 inserted through the openings in the finger-head 44 and in the opening 60 in the bracket 42. Nails N having been supplied to the jack-passages upon the drivers 12, a shoe S is jacked and a heel H applied to the heel-seat. The plate 22 is initially spaced from the tread-surface of the heel; the fork 30 is substantially separated from the lower portion of the sides of the heel; while at the rear the cushioned surface of the yieldable finger-casing 48 lies in proximity to the center of the rear of the heel. This is as appears in Fig. 1. The position of the fork is such that the operator has ample space to introduce his fingers at the opposite sides of the heel to correctly locate it transversely. Upon depression of the treadle of the machine, the plate 22 approaches the tread-surface of the heel, but, before it makes contact, the cushioned surface 66 of the finger engages the heel, exerting substantially all its

force to urge the breast against the shoulder on or cut in the outsole s of the shoe. As the descent of the tread-plate continues and it seats itself upon the heel, the spring 54 yields, so the forward force exerted by the finger is limited to that necessary to maintain a tight joint at the breast, until the tread-plate effects the clamping of the work (Fig. 2). Then the drivers 12 rise to insert the heel-attaching nails. The machine having performed its power-cycle, the head P is retracted and the heeled shoe may be removed from the jack.

If the heel to be attached has a relatively heavy pitch, so the fork 30 may effectively be used to resist rearward displacement, the locking pin 36 for the compensating mechanism is removed from its openings; the pin 56 is taken out of the openings in the finger E and its supporting bracket; the finger turned rearwardly and upwardly; and the pin placed in the finger-openings and the bracket-opening 62. The finger now is ineffective, and the heel is first engaged by the tread-plate and then by the rear fork. If either of the arms of the fork strikes the side of the heel before the other, the capacity of the body of said fork to slide laterally upon the mounting 23 allows it to adjust itself so the arms bear equally. With both the tread and rear members resting upon the heel, the final clamping proceeds as is usual in compensating hold-downs.

Having described my invention, what I claim as new and desire to secure by Letters Patent of the United States is:

- 35 1. In a heel-attaching machine, a support for a shoe and a heel, a pressure-head movable toward and from the support, a heel-tread-engaging member carried by the head, and a member yieldable upon the head and contacting with the rear of the heel before the engagement of the associated member with the tread.
- 40 2. In a heel-attaching machine, a support for a shoe and a heel, a pressure-head movable toward and from the support, a tread-plate carried by the head, a mounting attached to the head, and a spring-actuated plunger movable in the mounting for engagement with the rear of a heel upon the support, it being arranged to reciprocate in the mounting in a direction longitudinally of the shoe-bottom.
- 45 3. In a heel-attaching machine, a support for a shoe and a heel, a pressure-head movable toward and from the support, a heel-tread-engaging member carried by the head, a plurality of members carried by the head for engagement with the rear of the heel, and means arranged to secure one of the rear members in either an active or an inactive position.
- 50 4. In a heel-attaching machine, a support for a shoe and a heel, a pressure-head movable toward and from the support, a tread-plate carried by the head, a mounting attached to the head, a fork and a spring-actuated plunger carried by the mounting for engagement with the rear of the heel, and means arranged to secure the plunger in either an active or an inactive position.
- 55 5. In a heel-attaching machine, a support for a shoe and a heel, a pressure-head movable toward and from the support, a tread-plate carried by the head, a mounting attached to the head at the rear of the support, a fork free to slide upon the mounting transversely of the heel, a spring-actuated plunger movable upon the mounting, and means arranged to secure the

plunger in either an active or an inactive position.

6. In a compensating heel-holddown, a pressure-head, two racks guided for reciprocation in the head, means for communicating the movement of one rack to the other, means arranged to secure the racks against relative movement, a heel-tread-plate carried by one rack, and a yieldable member movable upon the other rack for engagement with the rear of the heel while the racks are held against relative movement.

7. In a compensating heel-holddown, a pressure-head, two racks guided for reciprocation in the head, a pinion communicating the movement of one rack to the other, means arranged to secure the racks against relative movement, a heel-tread-plate carried by one rack, a bracket attached to the other rack and having a projecting spindle, a casing guided upon the spindle for engagement with the rear of the heel, and a spring interposed between the spindle and casing.

8. In a compensating heel-holddown, a pressure-head, two racks guided for reciprocation in the head, a pinion communicating the movement of one rack to the other, means arranged to secure the racks against relative movement, a heel-tread-plate carried by one rack, a fork carried by the other rack for engagement with the rear of a heel, a spring-actuated plunger carried

by said other rack for engagement with the rear of the heel, and means arranged to secure one of the rear engaging members in an active or an inactive position.

5 9. In a compensating heel-holddown, a pressure-head, two racks guided for reciprocation in the head, a pinion communicating the movement of one rack to the other, means arranged to secure the racks against relative movement, a heel-tread-plate carried by one rack, a fork carried by the other rack for engagement with the rear of a heel, a bracket attached to said other rack, a spring-actuated plunger pivoted upon the bracket for engagement with the rear of the heel, and means arranged to secure the plunger upon the bracket in an active or an inactive position.

10 15 19. In a compensating heel-holddown, a pressure-head, two racks guided for reciprocation in the head, a pinion communicating the movement of one rack to the other, means arranged to secure the racks against relative movement, a heel-tread-plate carried by one rack, a bracket attached to the other rack, a spindle pivoted upon the bracket, there being openings in the bracket and spindle adapted to receive a pin to secure the spindle in different positions about its pivot, a casing guided upon the spindle for engagement with the rear of a heel, and a spring interposed between the spindle and the casing.

20 25 WILLIAM W. WOOLDRIDGE.
